INDOOR GAME APPARATUS

Louis Burn, Sunnybank, Morden, Surrey, England

Application November 1, 1932, Serial No. 640,726
In Great Britain November 30, 1931

13 Claims. (Cl. 273—144)

This invention relates to indoor games and has for its object to provide an indoor game apparatus of the chance type.

In the improved apparatus in accordance with the present invention, a number of balls, discs or the like (hereinafter called generally rollers) of varying colours or other characteristics are placed within a container which is rotated or otherwise moved so as to cause the rollers to be mixed.

Means are provided whereby at any desired moment one or more rollers may be delivered from the container or alternately the chosen roller or rollers may be exposed.

The apparatus in its preferred form comprises a rotary drum into which are inserted twelve balls, say five red, four white and three black, and the drum is so mounted as to be capable of rotating by means of a handle or like means provided for the purpose. The drum contains in its periphery three pivoted plates which normally close corresponding openings in the periphery of the drum when the drum is rotated in the normal direction for mixing the balls.

If the drum is given a turn in the opposite direction these fingers will drop downwards and cause three balls to be delivered from the drum. These pivoted plates are preferably all mounted on the same shaft and are provided with guiding grooves so that when the banker or like operator gives the reverse turn to the drum three balls are caused to roll out from the drum and move along the table or the like upon which the game is played.

It will thus be seen that the apparatus provides a device for mixing a number of balls or other rollers of varying characteristics and delivering a number of balls or the like of random characteristics.

Referring to the accompanying drawing which illustrates the invention in a diagrammatic manner:—

Figure 1 shows an elevation, of one form of apparatus designed for selection of three balls at a time.

Figure 2 is a sectional elevation of the drum.

Figure 3 is a plan view showing the drum in section.

Figure 4 is a sectional elevation of an alternative form of drum.

The drum A is provided with a central shaft B supported between frames C and a handle D is provided for rotation of the drum in either direction. The periphery of the drum is provided with three openings E having round end portions slightly larger than the balls F to be used in the

apparatus; these openings are in line and are normally closed by pivoted plates G which project.

These pivoted plates G are mounted upon a cross shaft H and a spring J normally closes them. Each finger has a bight K to receive a ball and is so shaped when the shaft H is rocked the ball then in the bight is allowed to fall through the opening E on to a guide track L but stops the next ball from passing through. On one or both ends of the shaft H is carried a ratchet lever M with 60 which engages a pawl N mounted upon a pivot P upon one or both of the frames C.

The pawl N is normally held in the position shown by a stop pin or like device not shown and it and the ratchet lever M are so shaped that 70 when the handle D is rotated clockwise the pawl N will move under the control of a spring Q and allow the ratchet lever M to click past.

If, however, the handle is rotated anti-clockwise the lever M is engaged by the pawl N so that the shaft H rocks and carries with it the plates G thus allowing to fall on to the track L the three balls that happen to be in the bights K. Division plates R are provided to guide the balls towards the apertures E.

Referring now to Figure 4 the drum a on the shaft b is provided with a radial guide d extending from the periphery to near the centre and a parallel guide e passing from the centre towards the periphery with a curved portion f. Another guide g starts with a curved portion h and then continues to the periphery at which suitable exit openings are provided.

If this drum is turned clockwise no delivery of balls takes place, but if turned anti-clockwise the lowest ball will first run down the guide e, around the shaft, into the curved parts h and finally out as shown by the arrow.

A separate inlet door c is necessary in this form of apparatus and division plates similar to those previously described, are provided to cause the separate balls to move in their own tracks.

What I claim is:—

1. An indoor game apparatus comprising a container for rollers of varying characteristics, means for mixing the rollers within the container by rotating a shaft in one direction, an aperture in the wall of said container, a closure member normally closing said aperture and carried on a spindle projecting outside said container, a ratchet lever carried on the projecting portion of said spindle and a pawl arranged in the path of said ratchet lever that when the container is rotated in one direction said ratchet lever clicks past said pawl and said closure member remains in 100

- closing position but when said container is rotated in the opposite direction the closure member is moved clear of said aperture.
2. An indoor game apparatus comprising a container for rollers of varying characteristics, means for mixing the rollers by rotating said container, a radial guide in said container extending from the periphery to a point before the center and a second guide parallel to said first-mentioned guide 10 and terminating in a semi-circular part concentric with the center of the container, the guides being so shaped that when the container is rotated in one direction the rollers become mixed therein but when rotated in the opposite direction a ball 15 is fed between the guides and finally ejected.
3. An indoor game apparatus comprising a container for rollers of varying characteristics, an aperture in said container, means for rotating said container in either direction, a closure for said 20 aperture, and ratchet means permitting said container to be rotated in one direction while the aperture remains closed and causing said closure to open when the container is rotated in the opposite direction.
4. An indoor game apparatus comprising a container for rollers of varying characteristics, means for mixing the rollers within the container on rotating a shaft in one direction, and means for automatically delivering a predetermined number 30 of rollers on rotating said shaft in the opposite direction.
5. An indoor game apparatus comprising a container for rollers of varying characteristics, means for mixing the rollers within the container on 35 rotating a shaft in one direction, and means for automatically displaying a predetermined number of rollers on rotating said shaft in the opposite direction.
6. In a game apparatus, a container for otherwise free rollers of varying characteristics, said container having a delivery opening, means for normally closing the opening against delivery on the rotation of the container in one direction to thereby mix the rollers, and means for automatically freeing the opening for delivery of the 40 balls on the rotation of the container in the opposite direction.
7. An indoor game apparatus comprising a container for rollers of varying characteristics, a plurality of apertures formed in the wall of the container, means for closing said apertures while the parts are rotated in one direction for mixing, and means for opening said apertures at intervals, said means being automatically operated on rotating said parts in the opposite 45 direction and incorporating a device for allowing only one ball to pass through each said aperture.
8. An indoor game apparatus comprising a container for rollers of varying characteristics, means for mixing the rollers by rotating said container, a plurality of openings in the wall of said container, pivoted plates positioned inside said container and normally closing said apertures, means for moving said plates inwardly to 50 enable a roller to pass through each said aperture, said plates being so shaped that they allow only one roller to pass through each time said apertures are opened.
9. An indoor game apparatus comprising a container for rollers of varying characteristics, means for mixing the rollers by rotating said 55
- container in one direction, a plurality of openings in the wall of said container, guide plates leading one roller centrally to each said aperture, pivoted plates normally closing said apertures, means actuated by rotating said container in the opposite direction for operating said pivoted plates to enable a roller to pass through each said aperture, said plates being so shaped that they allow only one roller to pass through each time said apertures are opened.
10. An indoor game apparatus comprising a container for rollers of varying characteristics, means for mixing the rollers within the container by rotating a shaft in one direction, an aperture in the wall of said container, a closure member normally closing said aperture and carried on a spindle projecting outside said container, a ratchet lever carried on the projecting portion of said spindle, and a pawl so arranged in the path of said ratchet lever that when the container is rotated in one direction said ratchet lever clicks past said pawl and said closure member remains in closing position but when said container is rotated in the opposite direction the closure member is moved clear of said aperture.
11. An indoor game apparatus comprising a container for rollers of varying characteristics, means for mixing the rollers by rotating said container, a radial guide in said container extending from the periphery to a point before the center, and a second guide parallel to said first-mentioned guide and terminating in a semi-circular part concentric with the center of the container, the guides being so shaped that when the container is rotated in one direction, the rollers become mixed therein but when rotated in the opposite direction a ball is fed between the guides and finally ejected.
12. An indoor game apparatus comprising an element container mounted for free rotation in either direction, a normally closed delivery member carried by the container and serving when operated in one direction to permit delivery of the elements within the container, and means arranged beyond the container and maintained in a predetermined relation thereto to actuate the delivery member to permit element delivery from the container, said means being without effect on the delivery member in the rotation of the container in the opposite direction, whereby under rotation in one direction the elements in the container are mixed and in operation of the container in the opposite direction the elements are delivered from the container.
13. An indoor game apparatus comprising a container for the reception of loose elements, a delivery member normally closing the container against delivery of said elements therefrom, said member being operative to permit delivery of the elements from the container, an operating projection carried by the member and extending beyond the container, and means interposed in the path of travel of said projection, said means in the movement of the container in one direction operating said projection to move the member relative to the container for element delivery from the container, said means on movement of the container in the opposite direction being displaced by the projection without affecting the member.

LOUIS BURN.
